UNITED STATES PATENT OFFICE

HARRY KORETZKY, OF JERSEY CITY, NEW JERSEY, MAX HOROWITZ, OF BROOKLYN, NEW YORK, AND ANTHONY J. DESIMONE, OF LYNDHURST, NEW JERSEY, ASSIGNEES TO BRIGHT STAR BATTERY COMPANY, OF HOBOKEN, NEW JERSEY, A CORPORATION OF NEW YORK

FLASH LIGHT

Application filed March 27, 1931. Serial No. 525,804.

This invention relates to improvements in electrical switch mechanism and more especially to switches adapted for use with portable electric lamps, such, for example, as 5 the well-known flashlight.

An object of this invention is a flashlight switch which is simple in structure, easy to operate, inexpensive to manufacture and in which means are provided to prevent accidental closing of the circuit.

Other objects, novel features and advantages of this invention will be apparent from the following specification and accompanying drawings, wherein:

15 Fig. 1 is an elevation of a flashlight equipped with switch mechanism embodying the invention;

Fig. 2 is an enlarged section on the line 2-2 of Fig. 1;

20 Fig. 3 is a bottom view of a switch mechanism;

Fig. 4 is a fragmentary section on the line 4-4 of Fig. 2;

25 Fig. 5 is a section similar to Fig. 2 on the line 5-5 of Fig. 6;

Fig. 6 is a bottom view of a modification;

Fig. 7 is a fragmentary section on the line 7-7 of Fig. 6;

30 Fig. 8 is a bottom view of another modification;

Fig. 9 is a section on the line 9-9 of Fig. 8;

Fig. 10 is a bottom view of a further modification;

35 Fig. 11 is a section on the line 11-11 of Fig. 10;

Fig. 12 is a bottom view of a still further modification, and

40 Fig. 13 is a section on the line 13-13 of Fig. 12.

Referring now more especially to Figs. 1 to 4 inclusive, 10 designates the tube of a flashlight and 11 designates the switch mechanism attached to the outer wall of the tube. This switch mechanism comprises a casing or escutcheon plate 12 having a flange in which are provided holes for rivets by 45 which the same is attached to the tube. A

50 slide or housing 13 is attached to the casing 12 by means of tongues 14 which extend

from the slide through slots in the casing 12, the inner ends of the tongues being bent over. The slide 13 is tubular and has its upper edge rolled inwardly as shown in Fig. 2 to form a shoulder 13a. A leaf spring 55 15 is attached at one end to the casing by means of a rivet or the like 15a and is provided with a hump or offset 16 which extends through an aperture in the casing 12 into the slide 13. A plate or disk 17 rests 60 on the hump 16 and engages the shoulder 13a. The free end of the leaf spring 15 extends obliquely downwardly and is adapted to pass through a slot in the casing 10 into engagement with a contact strip 18 65 supported by the casing 10 with a strip of insulating material 19 interposed. The strips 18 and 19 are fastened together with rivets, the heads of which are countersunk in the insulating strip 19, thereby avoiding 70 contact with the casing 10. Between the hump 16 and the rivet 15a the spring 15 is offset downwardly at 20. A slide 21 is held against the under face of the casing 12 by the tongues 14 which fit into notches in the 75 slide so that the latter is movable with the housing 13. The hump 16 is cut away to provide shoulders 24 and shoulders 25 while the slide is provided with inwardly projecting portions 26 which are adapted in one 80 position of the slide to overlie the shoulders 24 and hold the contact member in circuit closing position and in another position to underlie the shoulders 25 and prevent flexing 85 of the contact member and in an intermediate position to permit free movement of the contact member. The slide 21 can be moved from its intermediate position into position to prevent flexing of the contact member merely by pressure on the housing 13. How- 90 ever, the slide is locked by the shoulders 24 against movement into its other position and can be moved from the intermediate position into such position only after the contact member has been flexed, this flexing 95 being accomplished by pressure on the disk 17.

The strip 18 may be slidably supported by the tube 10 if the switch mechanism is used with focusing flashlight of the type 100

disclosed in co-pending application, Serial No. 525,805 filed March 27, 1931. In such event, the contact member 18 may be connected to a slide 27 mounted on the casing 12 by means of tongues 28 extending from the slide through the housing and through slots in the tube 10. With this arrangement, the flashlight may be focused and controlled by operation of the slides 13 and 27 by the use only of the thumb of the hand in which the flashlight is being held.

In the modification disclosed in Figs. 5 to 7 inclusive, the housing 13 is slidably attached to the casing 12 by tongues 14 which extend from the housing through slots in the casing and have their inner ends bent over and extending toward each other. The hump 16 of the spring 15 is cut away to provide shoulders 24 which are engageable by the tongues 14 to prevent movement of the casing 13 in one direction. The width of the hump 16 is less than the distance between the ends of the tongues 14.

The contact member 15 may be flexed by pressure on the plate on disk 17 to bring the free end of the contact member into engagement with the metal strip 18. When the contact member is flexed into circuit closing position, the casing 13 may be moved forward to lock the contact member in circuit closing position. However, the casing 13 cannot be slid forward until after the contact member has been flexed to move the shoulder 24 out of the path of the tongues 14. In this modification no means are provided to lock the contact member in circuit open position.

In the modification disclosed in Figs. 8 and 9, the housing 13 is slidably mounted on the casing 12 by means of tongues 14 which fit into notches in the slide 21. The hump 16 is cut away to provide shoulders 25 under which the slide is adapted to lie to prevent flexing of the contact member 15, thereby holding the same in circuit open position. The contact member is provided with an oblique portion 15b which is adapted to be engaged by the slide 21 upon forward movement of the housing 13, thereby moving the contact member into circuit closed position in which it is held by the slide. With the housing 13 in the position shown in Fig. 9, the contact member 15 may be flexed by pressure disk 17.

In the modification disclosed in Figs. 10 and 11, the housing 13 is slidably attached to the casing 12 by tongues 14. The hump 16 is cut away to provide shoulders 25 which are adapted in one position of the housing 13 to engage the tongues 14, thereby locking the contact member 15 in circuit open position. With the housing 13 in the position shown in Fig. 11, the contact member may be flexed by pressure on the disk 17. By cutting away the hump 16, the tongues 15c

are formed which are provided with oblique surfaces engageable by the tongues 14 to move the contact member into circuit closing position upon forward movement of the slide, the contact member being held in this position by the tongues 14.

In the modification disclosed in Figs. 12 and 13, the slide or housing 13 is mounted on the casing 12 by means of tongues 14. A button 28 has a flange 29 which rests on the free end of the contact member 15 with the main portion of the button projecting through apertures in the casing 12 and slide 13. The contact member 15 is provided with obliquely arranged tongues 15c which are engageable by the tongues 14 to move the contact member into circuit closing position upon forward movement of the slide 13, the contact member being held in this position by the tongues 14. The downward movement of the contact member 15 moves the button 28 to permit forward movement of the slide 13. With the parts in the position shown in Fig. 13, the contact member may be flexed into circuit closing position by pressure on the button 28.

In each of the modifications accidental operation of the flashlight is prevented by having the pressure member guarded by an annular upstanding ridge. Also in the various modifications, the plate or disk 17 is embossed with a suitable figure which may be in the nature of a trade mark, if desired.

The switch mechanism may be combined with focusing means as shown in Figs. 1 to 11 when used with a focusing flashlight or may be used by itself as a non-focusing flashlight. In the latter event, the slide 27 will be dispensed with and the contact member 18 will be rigidly fixed to the casing 10.

It is of course understood that various modifications may be made in the structure above described, without in any way departing from the spirit of the invention as defined in the appended claims.

We claim:

1. Switch mechanism comprising a casing, a contact member within said casing and fixed thereto at one end and having an offset portion at its other end, a tubular housing slidably mounted on said casing and enclosing said offset portion, a disk resting on said offset portion, an annular shoulder in said housing engageable by said disk, and means movable with said housing to engage said contact member for holding it in circuit closed position after having been moved into such position.

2. Switch mechanism comprising a casing having an aperture, a contact member fixed at one end to said casing and having an offset portion projecting through said aperture, a tubular housing slidably mounted on said casing and enclosing said offset portion,

- an annular shoulder in said housing, a disk resting on said offset portion and engaging said shoulder, and means movable with said housing for locking the contact member in circuit closed position after it has been moved into such position. 5
3. Switch mechanism comprising a casing having an aperture, a contact member fixed at one end to said casing and having an offset portion projecting through said aperture, a tubular housing slidably mounted on said casing and enclosing said offset portion, an annular shoulder in said housing, a disk resting on said offset portion and engaging said shoulder, means movable with said housing for locking the contact member in circuit closed position after it has been moved into such position, and means for preventing movement of said housing in one 10 direction until after the contact member has been moved into circuit closed position. 15
4. Switch mechanism comprising a casing having an aperture, a contact member fixed at one end to said casing and having an offset portion projecting through said aperture, a tubular housing slidably mounted on said casing and enclosing said offset portion, a shoulder in said tubular housing, a disk resting on said offset portion and engaging said shoulder, a plate within said casing connected to said housing for movement therewith, said plate and contact member being provided with coacting shoulders for locking the contact member in 20 circuit open position in one position of the plate and in circuit closed position in another position of the plate. 25
5. Switch mechanism comprising a casing having an aperture, a contact member fixed at one end to said casing and having an offset portion projecting through said aperture, a tubular housing slidably mounted on said casing and enclosing said offset portion, a shoulder in said tubular housing, a disk resting on said offset portion and engaging said shoulder, a plate within said casing connected to said housing for movement therewith, said plate and contact member being provided with coacting shoulders for locking the contact member in 30 circuit open position in one position of the plate and in circuit closed position in another position of the plate, said plate being locked against movement in one direction until after the 35 contact member has been moved into circuit closed position. 40
6. Switch mechanism comprising a casing having an aperture, a contact member fixed at one end of the casing and having an offset portion projecting through said aperture, a tubular housing slidably mounted on said casing and enclosing said offset portion, a shoulder in said housing, a disk resting on said offset portion and engaging said shoulder and means movable with said 45
- housing for holding said contact member in circuit closed position after it has been moved to such position. 50
7. Switch mechanism comprising a casing having an aperture, a contact member fixed at one end of the casing and having an offset portion projecting through said aperture, a tubular housing slidably mounted on said casing and enclosing said offset portion, a shoulder in said housing, a disk resting on said offset portion and engaging said shoulder and means movable with said housing for holding said contact member in circuit closed position after it has been moved to such position, said slide being locked against movement in one direction by said contact member until after said contact member has been moved to circuit closed position. 55
8. Switch mechanism comprising a casing having an aperture, a contact member fixed at one end to said casing and having an offset portion projecting through said aperture, a tubular housing slidably mounted on said casing and enclosing said offset portion, a disk resting on said offset portion, means for retaining said disk in said housing, said contact member having oblique portions, and means movable with said housing into engagement with said oblique portion for moving the contact member into circuit closed position. 60
9. Switch mechanism comprising a casing having an aperture, a contact member fixed at one end to said casing and having an offset portion projecting through said aperture, a tubular housing slidably mounted on said casing and enclosing said offset portion, a disk resting on said offset portion, means for retaining said disk in said housing, said contact member having oblique portions, means movable with said housing into engagement with said oblique portion for moving the contact member into circuit closed position and shoulders formed on said contact member for engagement by said means to hold the contact member in circuit open position. 65
10. Switch mechanism comprising a casing having an aperture, a contact member fixed at one end to said casing and having an offset portion projecting through said aperture, a tubular housing slidably mounted on said casing and enclosing said offset portion, a disk resting on said offset portion, means for retaining said disk within said housing, a plate within said casing connected to said housing for movement therewith, said contact member having an oblique portion engageable by said plate for moving the contact member into circuit closed position. 70
11. Switch mechanism comprising a casing having an aperture, a contact member fixed at one end to said casing and having an offset portion projecting through said 75

aperture, a tubular housing slidably mounted on said casing and enclosing said offset portion, a disk resting on said offset portion, means for retaining said disk within said housing, a plate within said casing connected to said housing for movement therewith, said contact member having an oblique portion engageable by said plate for moving the contact member into circuit closed position, and shoulders on said contact member engageable by said plate in one position thereof to lock the contact member in circuit open position.

In testimony whereof, we have signed
our names to this specification.
